(57) **CLAIM**

The ornamental design for a saw blade, as shown and described.

DESCRIPTION

FIG. 1 is a front view of a saw blade showing the new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The dash-dash broken lines shown in FIGS. 1-7 illustrate portions of the saw blade that form no part of the claimed design; The dot-dash broken lines shown in FIGS. 6-7 define the bounds of the claimed design and form no part thereof. The claim is directed to shaded surfaces.

Any unshaded surface shown in broken or between solid and broken lines forms no part of the claimed design.

1 Claim, 7 Drawing Sheets
